United States Patent Office

Des. 233,449
Patented Oct. 29, 1974

233,449

AMPOULE WITH PARTICLE TRAP OR SIMILAR ARTICLE

Otto Zauner, Vineland, N.J., assignor to
Owens-Illinois, Inc., Toledo, Ohio

Filed May 18, 1973, Ser. No. 361,843

Term of patent 14 years

Int. Cl. D24—04
U.S. Cl. D32—1

FIG. 2

FIG. 1

FIG. 3

FIG. 1 is an elevation view of an ampoule with particle trap or similar article showing my new design.

FIG. 2 is a top or plan view of the ampoule with particle trap or similar article shown in FIG. 1.

FIG. 3 is a bottom plan view of the ampoule with particle trap or similar article shown in FIGS. 1 and 2.

I claim:

The ornamental design for an ampoule with particle trap or similar article, as shown.
